UNITED STATES PATENT OFFICE.

MOSES S. WALTON AND WALTER B. JOSLYN, OF LOS ANGELES, CALIFORNIA.

DESIGN FOR A MOTOR-TRUCK BODY.

46,554.

Specification for Design.

Patented Oct. 13, 1914.

Application filed August 19, 1913. Serial No. 785,564. Term of patent 7 years.

To all whom it may concern:

Be it known that we, MOSES S. WALTON and WALTER B. JOSLYN, citizens of the United States, residing at Los Angeles, in the county of Los Angeles, State of California, have invented a new, original, and ornamental Design for Motor-Truck Bodies, of which the following is a specification, reference being had to the accompanying drawing, in which the figure is a perspective view of our truck body.

We claim:—

The ornamental design for a motor truck body as shown.

MOSES S. WALTON.
WALTER B. JOSLYN.

Witnesses:

ANNIE HARTENSTEIN,
W. MARION SPEARS.
